UNITED STATES PATENT OFFICE.

CALVIN W. VAUGHN, OF CUYAHOGA FALLS, OHIO, ASSIGNOR TO THE TURNER,
VAUGHN TAYLOR COMPANY, OF SAME PLACE.

BRICK-MACHINE.

SPECIFICATION forming part of Letters Patent No. 430,978, dated June 24, 1890.

Application filed January 2, 1890. Serial No. 335,606. (No model.)

To all whom it may concern:

Be it known that I, CALVIN W. VAUGHN, a citizen of the United States, residing at Cuyahoga Falls, in the county of Summit and State 5 of Ohio, have invented a certain new and useful Improvement in Brick-Machines, of which the following is a specification.

My invention has relation to improvements in machines for making pressed brick from 10 plastic material, and is especially designed for making brick from prepared silica.

The object of my invention is to produce a new and improved machine for making pressed brick which shall be automatic in its 15 operation, and to embody in such a machine a mold of peculiar construction, an automatic device for charging the mold, means for removing the perfect brick from the mold, apparatus for effecting intense pressure upon 20 the plastic material in the mold, and a combination of devices which shall cause the separate parts to severally co-operate to produce the desired result.

To these ends my invention consists in the 25 novel and peculiar construction and combination of parts, hereinafter described, and then specifically pointed out in the claims, reference being had to the accompanying drawings, which form a part of this specification.

30 In the accompanying drawings, in which similar letters of reference indicate like parts, Figure 1 is a front elevation of my improved machine; Fig. 2, a side elevation; Fig. 3, a vertical central section in a plane from front 35 to back; and Figs. 4, 5, and 6, detached detail views of parts of the machine, hereinafter fully described.

Referring to the drawings, A is a bed-plate, which rests on cast side frames B B, and on 40 top of which are bolted two upright cast beams C C, which in turn support a steam-cylinder D. The cylinder D is provided with a valve D', by which the entrance and exit of steam at either end can be controlled, and with a 45 piston E' and piston-rod E, which latter, for the purpose of insuring directness of movement, extends through each cylinder-head, where suitable stuffing-boxes prevent the escape of steam. The lower end of the piston- 50 rod E is keyed to a cross-head I, which slides

in guides J J, attached to the upright beams C C.

The bed-plate A has a plane upper surface and through the center an opening larger in each direction than the brick to be made, 55 about and beneath which opening extends a heavy re-enforced flange A', integral with the bed-plate. This opening in the bed-plate and flange constitute a chamber for the reception of a casting G, which is arranged to enter and 60 fit the chamber with its top flush with the top of the bed-plate and has an outwardly-projecting flange at its base.

In the casting G is an opening, in which fits and rests a block H, the top of which is flush 65 with the top of the casting and of the size and shape of the desired brick, and from which extends downwardly a short shaft H'.

On top of the bed-plate A is a heavy cast block F, having a central orifice of the size of 70 the desired brick placed to register accurately above the block H, and sufficiently exceeding the size of said block to permit it to pass up through it.

The block F, bed-plate A, and casting G are 75 united by heavy bolts, as shown, the blocks F and H constituting the sides and bottom of the brick-mold.

Attached to the cross-head I is a plunger K, of the same horizontal shape and area as the 80 block H, and which is arranged to descend with the downstroke of the piston-rod E and enter the mold F until its bottom is even with the top of said mold, thereby compressing the material in said mold.

85 The valve D' is operated to cause the down and up strokes of the piston E' by a lever L, pivoted to the front of the bed-plate, and connected at one end by a connecting-rod L' with a short lever M on the end of the valve-stem. 90 The other end of the lever M is connected by a rod N' with one end of a lever N, pivoted to one of the beams C, the other end of which lever extends inward, so as to be engaged by the cross-head I in its upward stroke, and thereby automatically operate the valve D' to prevent 95 the further entrance of steam.

The casting G, blocks H and F, and plunger K are made detachable, so that different sets for assorted sizes of brick may be substituted. 100

On the block F, and extending beyond it to the front and rear, is a thin plate F', having upper side flanges on its front part, and an opening of the size of and which registers with the opening in the mold. 5

Resting on and fitted to slide between the flanges of the plate F is a feeding-box O, which consists of a rectangular box open at the front and having openings through the top and bottom near the rear end, exceeding in a front and rear direction the size of the opening in the mold. Inside this box is a sliding partition O', operated by a hand-screw O'', which constitutes with the sides and back of the box 15 an adjustable gage for the charge of plastic material for the mold.

Contiguously above and toward the front of the box O is a hopper P, open at top and bottom and supported on cross-bars P', attached to the beams C C. Journaled in suitable bearings on the upper rear part of the side frames B B is a shaft Q, on which is mounted a crank-arm Q', connected with one end of the cross-head I by a link or connecting-bar I'. Mounted in alignment with each other on the shaft Q are two slotted crank-arms R R, severally connected on opposite sides with the box O by connecting-rods R' R'. By this arrangement the box O is caused 25 to slide to the front as the piston makes its downward stroke until its open top registers with the lower end of the hopper, and to slide back with the return-stroke of the piston until its bottom opening is above the opening in the plate F' and block F.

Near the lower front of the side frames B B is a shaft S, on the center of which is mounted a crank-arm S', connected with the shaft H' by an adjustable pitman S'', so that 40 as the shaft S is revolved the block H will be forced up through the block F and plate F' and raise the completed brick out of the mold until it is even with the top of the plate F'. On the outer end of the shaft S is a slotted crank-arm T, to which is pivoted a hook T', constantly forced toward the back of the machine by a coiled spring T'', and from the inside near the the upper end of which projects a short pin U, Fig. 1.

Attached to the side frame B nearest the hook T' is a block V, on the lower face of which is a ledge V', through which is a diagonal groove U', and along and outside of which ledge is a guard-bar V'', Figs. 2, 4, and 5.

The operation of the various parts is as follows: Assuming the piston to be at the end of the downstroke, the box O is then at the front, with its opening beneath the lower end of the hopper P, from which the plastic material with which it has already been charged falls and fills the space between the back of the box O and the partition O'. As the piston rises on the return-stroke, the following operations take place: The upper outer corner of the crank-arm Q' in its upward movement engages the hook T' and carries it upward and causes, through the connected parts

hereinbefore described, the block H to rise through the block F and plate F', carrying the completed brick from the mold, until its top 70 is even with the top of the plate F.. The crank-arm Q' and hook T' are so arranged in relation to each other that at the moment the top of the block H is even with the upper face of the plate F' the hook T' is released 75 from the upper corner of the crank-arm Q' by the lower corner encountering and pushing forward the body of the hook, and simultaneously by the same movement the pin U passes onto the back end of the ledge V', 80 along which it slides, moved by the lower corner of the crank-arm Q' in its continued ascent, until it reaches the groove U', through which it descends, permitting the hook T' and block H to fall to their original positions. 85 By this arrangement the block H remains stationary at the end of its upward stroke during a short interval in the movement of the other parts for the purpose of permitting the completed brick to be pushed off, as hereinafter described. Commencing simultaneously with the operation last described, the box O slides backward, its top closing the lower end of the hopper P, and its back end encountering and pushing the completed brick off from the block H until at 90 the end of the stroke its bottom opening is brought above said block, whence as the block descends the charge of material falls into the mold. As the piston descends the 95 box O is again forced forward to its original position, and the plunger K enters the mold and presses the plastic material therein into form. As thus described the block H is arranged to descend by gravitation alone; but 100 if for any reason it should not do so, I insure its descent by placing on the end of the shaft S opposite, and turned in the opposite direction to the crank-arm S', a crank-arm W, Fig. 6, to which is pivoted a rod W', having at its 105 upper end a slot resting on a pin I' on the end of the cross-head I. By this arrangement if the block H does not descend by gravitation it will be forced to do so by the pin I' engaging in its ascent the upper end of the 110 slot in the rod W', and thereby causing a partial rotation of the shaft S.

Having thus described my invention, I claim—

1. In a machine of the class specified, the 115 combination, with the cross-head I and rock-shaft Q, connected by the link I', and crank-arm Q', of the box O, slotted crank-arms R R, and connecting-rods R' R', to cause said box to move across the line of motion of and simultaneously with the movement of said cross-head, substantially as shown and described.

2. In a machine of the class specified, the 120 combination, with the cross-head I, plunger K, mold F, and block H, connected with a 125 crank-arm on the rock-shaft S, of the hook T', arranged to turn the rock-shaft S, and the crank-arm Q', connected with said cross-head

I and arranged to engage and raise the hook T', substantially as shown and described, and for the purpose specified.

3. In a machine of the class specified, the combination, with the mold and the movable bottom adapted to pass upward through said mold, of a hook, as T', arranged to raise said movable bottom and having an inward projection or pin, as U, of a crank-arm, as Q', to raise, release, and push forward said hook, and a ledge, as V', to engage said projection U as said hook is released, and a groove, as U', to permit its descent as said hook is pushed forward, substantially as shown and described.
- 15 4. The combination, with the hook T', hav-

ing the projection U, and the ledge V', having the groove U', of the guard-bar V'', to retain said hook against said ledge, substantially as shown and described.

5. The combination, with the rock-shaft S 20 and cross-head I, of the crank-arm W, slotted shaft W', and pin I'', substantially as shown and described, and for the purpose specified.

In testimony that I claim the above I hereunto set my hand.

CALVIN W. VAUGHN.

In presence of—

ORLANDO WILCOX,

C. E. HUMPHREY.
